FREQUENCY STABILIZATION OF MICROWAVE OSCILLATIONS

Lowell E. Norton, Princeton, N. J., assignor to Radio Corporation of America, a corporation of Delaware

Application May 29, 1950, Serial No. 164,977

10 Claims. (Cl. 250—36)

This invention relates to methods and systems utilizing molecular resonance of gases for stabilization of the frequency of microwave oscillations.

The present invention is an improvement upon that disclosed in copending application Serial No. 5563 in which a modulated Stark effect is used for frequency stabilization.

In accordance with the present invention, the microwave oscillations are impressed upon two confined bodies of gas which in the absence of Stark fields exhibit sharp molecular resonance at a frequency or frequencies substantially displaced from the desired frequency of the microwave oscillations. To provide an error-signal of polarity reversing with change in sense of the deviation of the oscillations from the desired frequency, there are produced, in the bodies of gas, Stark fields having direct-current components which shift the molecular resonances or absorptions to frequencies respectively higher and lower than the desired frequency of the oscillations and having pulsating components of opposite phase effective in unison to sweep the molecular absorptions toward and from the aforesaid desired frequency. The microwave energies transmitted by the bodies of gas so subjected to Stark fields are demodulated and thence combined, as in an amplitude or phase-comparator network, to produce an error-signal for use in control of frequency of the oscillations.

The invention further resides in methods and systems having the features of novelty and utility hereinafter described.

For a more detailed understanding of the invention, reference is made to the accompanying drawing in which:

Fig. 1 is a block diagram of a frequency control system using the invention;

Figs. 2A, 2B, and 3A-3C are explanatory figures referred to in discussion of Figs. 1, 4 and 5;

Fig. 4 is a block diagram of a modification of Fig. 1; and

Fig. 5 is a schematic diagram of components suited for use in the system of Fig. 4.

Referring to Fig. 1, the oscillator 10 may be a klystron, magnetron or other generator of microwave oscillations whose frequency is to be stabilized; alternatively, it may be a medium-frequency oscillator followed by a series of harmonic generators for producing microwave oscillations. In either event, the microwave energy is impressed, as by transmission lines 12A, 12B of waveguide or concentric line type, upon two enclosures 11A, 11B containing gas, such as ammonia, which exhibits sharp molecular resonance at microwave frequencies. Various examples of suitable gas and frequencies at which they exhibit molecular absorption are mentioned in copending applications including Serial No. 1240.

Each of the gas cells may be a chamber or length of waveguide having windows 9, 9 of quartz, mica or other material transparent to the microwave energy and which can be sealed to the walls of the cell to form a gas-tight seal for enclosure of the gas at suitably low pressures,

2

for example of the order of 0.01 millimeter of mercury.

In general, assuming an absorption line of a gas to occur at a frequency f_0 , the frequency f to which the maximum absorption is displaced upon subjection of the gas to a Stark field having the value e may be expressed as

$$(1) \quad f = f_0 + \beta e^2$$

where β = a constant depending upon the particular gas and line.

If the Stark field has both a D. C. and sinusoidal component, the voltage e applied to the Stark electrode may be defined as

$$(2) \quad e = E (1 + m \sin pt)$$

where m = modulation factor

pt = time-phase angle

E = magnitude of D. C. field

The displaced frequency at which maximum absorption occurs at any instant would therefore be expressed as

$$(3) \quad f = f_0 + \beta E^2 \left(1 + \frac{m^2}{2} + 2m \sin pt - \frac{m^2}{2} \cos 2pt \right)$$

If the modulation factor be made small, i. e., that $m \ll 1$, then the frequency of the shifted absorption may be simply expressed as

$$(4) \quad f \approx f_0 + \beta E^2 (1 + 2m \sin pt)$$

When the alternating or pulsating component of the Stark field passes through zero, the absorption frequency will be at its displaced mean value, expressed as

$$(5) \quad f \approx f_0 + \beta E^2$$

At the maximum positive and negative peak values of the modulation, the corresponding absorption frequencies are respectively

$$(6) \quad f \approx f_0 + \beta E^2 (1 + 2m)$$

$$(7) \quad f \approx f_0 + \beta E^2 (1 - 2m)$$

If the zero or quiescent value of the displaced absorption be denoted as

$$(8) \quad f_01 = f_0 + \beta E^2$$

the absorption frequency will vary in both directions therefrom with the modulation by amounts $\pm 2m\beta E^2$.

Specifically applying the foregoing to Fig. 1, assuming the absorption line L_1 of gas within the cell 11A is normally of frequency f_0 and the desired frequency of the microwave oscillations is frequency f_k , there may be applied to the Stark electrode 20A within the gas cell 11A a direct-current voltage such as derived from battery 21, or equivalent D. C. source, of such magnitude as to shift the absorption frequency to the frequency $f_0 + \beta E^2$. This displaced line L_A , as appears in Fig. 2A, is somewhat higher in frequency than the desired frequency f_k of the oscillations.

For simplicity of explanation, it will be assumed that the same gas is used in the second enclosure 11B, and consequently has an absorption line L_2 also at the frequency f_0 . The direct-current component of the voltage applied to the Stark electrode 20B is of suitably lower value bE_1 (where b is a constant later defined) so that this absorption line, as shown by line L_B , Fig. 2B, is displaced to lesser amount. The frequency $f_0 + \beta b^2 E_1^2$ of the displaced absorption line L_B is somewhat lower than the desired frequency f_k of the microwave oscillations.

The same source of direct current 21 may be used for supplying the biasing potential of Stark electrode 20A, 20B or different sources may be used. In any event, the relative magnitudes of the two D. C. biasing voltages applied to the Stark electrodes are selected or adjusted so that absorption lines L_1 , L_2 of the two bodies of gas, as appears in Figs. 2A and 2B, are displaced from their original frequencies, whether the same or different, to fre-

quencies respectively above and below the desired frequency f_k of the generated oscillations.

Resistors 24 are inserted in the leads from the D. C. biasing battery to the Stark electrodes to permit modulating oscillator 22 to vary the Stark electrode potentials periodically.

The Stark electrodes 20A, 20B are also suitably connected or coupled to a source of alternating or pulsating voltage, such as a low-frequency oscillator exemplified by block 22 of Fig. 1, whose output wave form may be sinusoidal, triangular or any other desired shape. Thus, the shifted absorption line L_A of gas in cell 11A is periodically swept over the range $\pm 2m\beta E_1^2$ and the shifted absorption line of gas in cell 11B is swept at the same frequency or repetition rate over the range $\pm 2m_1 b^2 E_1^2$. The range $2m\beta E_1^2$ should be less than $(f_0 + \beta E_1^2) - f_k$ and range $2m_1 b^2 E_1^2$ should be less than $f_k - (f_0 + \beta b^2 E_1^2)$. If the sweep interval is made greater than this, then in the case of the amplitude comparison detector arrangement of Fig. 1 detectors 13 and 14 will each produce a voltage due to the maximum of the absorption envelopes and circuit operation will fail. The corresponding phase or coincidence detector method of Fig. 4 will not fail for this condition of extended sweep. The connection from one of the Stark electrodes to the source of modulating potential includes a 180° phase-shifter 23, of any suitable type, which insures that pulsating components of the Stark fields vary in phase opposition as shown by Figs. 3B, 3C so that the sweeping Stark lines in unison move toward and from the desired frequency f_k of the generated oscillations.

The connections from the modulator 22, or equivalent, includes a proportioning network, exemplified by a potentiometer 37 for adjusting the relationship of the modulation factors m, m_1 for the two Stark fields. For the preferred case where the desired frequency f_k of the oscillations is midway between the displaced Stark line frequencies $(f_0 + \beta E_1^2)$ and $(f_0 + \beta b^2 E_1^2)$, the ratio of the modulation factors should be

$$b^2 = \frac{m}{m_1}$$

Capacitors 25, 25 are blocking condensers, used when necessary, to preclude flow of direct current from source 21 in the modulator or phase-shifter networks.

Assuming the output of the modulator 22 is sinusoidal (curve M of Fig. 3A); during each cycle of the modulation, the molecular absorptions or resonances of the two gas cells 11A and 11B as shown by curves A and B of Figs. 3B, 3C, sweep in unison from frequencies higher and lower than the desired frequency f_k in unison toward and from the desired frequency f_k . The modulation factors m, m_1 are so adjusted that each of the Stark lines L_A, L_B moves to the desired operating frequency because if the sweep ranges are less than indicated in Fig. 1, there is a dead zone centered on frequency f_k in which the oscillations may vary in frequency without, as herein-after explained, producing an error signal. The sweep range should not be substantially greater than indicated in Figs. 2A, 2B as has been explained.

The microwave energies respectively transmitted by the two gas cells whose Stark fields are modulation as above described, are respectively impressed upon demodulators—exemplified in Fig. 1 by the diodes 13 and 14 which may be replaced by crystal rectifiers or other non-linear resistances. In each cycle of the Stark field modulation, the output of each of the demodulators includes a pulse occurring as the sweeping Stark line passes through the frequency of the microwave oscillations being generated. When the frequency of the oscillations corresponds with the desired frequency f_k , the pulses of each pair are of the same magnitude and the output of a differential detector network 15 upon which the impulses are impressed is essentially zero. When the frequency of the generated oscillations is higher or lower than the desired frequency,

the polarity of the output of the comparator network is in each case of corresponding sense, reversing as the frequency deviation changes algebraic sign.

In the particular arrangement shown in Fig. 1, the comparator network 15 is of type similar to that disclosed in copending application Serial No. 596,242 which compares the relative amplitudes of each pair of pulses to produce an output whose polarity depends upon the sense of deviation of the frequency of the oscillations from the desired frequency f_k and of magnitude dependent upon the extent of the deviation. Specifically, the demodulators 13 and 14 are connected in opposition in series with two pairs of resistances 16-16 and 17-17, the output or error signal e_c appearing between the common terminals of resistors 17, 17 and 16, 16. The differential output of the two demodulators is impressed upon an integrating or smoothing network comprising resistor 18 and capacitor 19 so that the error signal for any given frequency deviation is of steady value rather than pulsating.

The sense and magnitude of the error voltage e_c may be determined by impressing it upon a vacuum tube voltmeter 8, or equivalent, and an operator may adjust a frequency control 26 of the oscillator in correction for the observed frequency-error. Preferably, however, the control voltage is applied to a frequency-control electrode of the oscillator tube or associated control tube automatically to stabilize the oscillator frequency. One specific arrangement for so automatically controlling the frequency of a microwave oscillator is herein later described.

The arrangement shown in Fig. 4 is similar to that of Fig. 1 except that the comparator network 15A is of type which compares the phase of the output pulses of the demodulators respectively associated with the Stark modulated gas cells 11A, 11B. Various forms of such phase comparator or coincidence detectors are disclosed in copending applications Serial Nos. 4497, now Patent No. 2,702,351 and 29,836, now abandoned. Specifically, as by a pair of rectifiers 13, 13, the microwave energy transmitted by cell 11B is converted to concurrent pairs of oppositely poled pulses applied to one input channel of the phase-comparator. Alternatively, and as shown in the aforesaid applications, a single rectifier may be used and a push-pull amplifier stage interposed between the demodulator and the comparator to provide the oppositely phased pulse output. The other channel, including the demodulator 14, supplies pulses of one polarity to another input circuit of the comparator. The phase relation between the pulses of the two channels depends upon the existing deviation from f_k of the frequency of the oscillations transmitted to the two Stark-modulated gas cells and reverses with reversal in sign of the frequency deviation.

The phase-comparator 15B specifically shown in Fig. 5 may be used with either of the aforesaid arrangements. It comprises a pair of diodes 27, 27, or equivalent nonlinear resistances which are connected in series and oppositely poled, their differential output current traversing the resistances 28, 28 in series with them. The error-voltage e_c , as indicated, is developed between the common terminal of resistors 28, 28 and the common terminal between the anode of one diode and the cathode of the other.

The push-pull input circuit of the comparator upon which the paired impulses of one channel are impressed comprises a pair of resistances 30, 30 connected in series with each other and in shunt to the resistors 28, 28, the condensers 29, 29 serving to block the direct current produced by the diodes. The input circuit for the second channel includes the resistor 31 connected between the common terminal of the resistors 30, 30 and ground or equivalent return point to apply each of these pulses to the diodes in phase.

There is produced by the phase-comparator the unidirectional signal voltage e_c depending in sense and magnitude upon the phase relations between the pulses re-

spectively applied to the two input circuits of the comparator. This signal voltage, smoothed by the integrating network 18, 19, 19A, may be applied directly to vary the potential of a frequency-control electrode of the klystron, magnetron or other microwave generator. In the particular arrangement shown in Fig. 5, the signal voltage is applied to vary the potential of the signal grid of a control tube 34 associated with a reflex klystron 32. The resistor 35 is common to the anode circuits of the control tube and the klystron, so that the potential of the anode of the klystron depends upon the potential of the signal grid of the control tube. Thus, any deviation in frequency of the generated oscillations from the frequency f_k , Figs. 2A, 2B, produces an error-voltage e_e which is applied in correction of that deviation.

The initial adjustment of the operating frequency of the klystron may be effected by adjustment of the potentiometer 36 in the grid circuit of the control tube or in other known manner including adjustment of resonant cavity dimensions of the klystron.

It shall be understood the invention is not limited to the specific systems above described and that changes and modifications may be made within the scope of the appended claims.

What is claimed is:

1. A control circuit for use in a system for controlling the frequency of microwave oscillations, said circuit comprising two confined bodies of gas each exhibiting sharp molecular absorption at a frequency displaced from the desired frequency of said oscillations, means for impressing said oscillations on said bodies of gas, means for producing in said bodies of gas direct-current Stark fields which displace the sharp molecular absorptions of said bodies of gas to frequencies respectively higher and lower than said desired frequency of the microwave oscillations, means for producing in said bodies of gas pulsating Stark fields of like frequency and opposite phase repeatedly and in unison to sweep said molecular absorptions from said higher and lower frequencies toward and from said desired frequency, means for demodulating the microwave energies respectively transmitted by said bodies of gas, and means for combining the demodulated energies to produce a signal of sense corresponding with the sense of deviation from said desired frequency of the microwave oscillations.

2. A circuit as in claim 1 in which the demodulated energies are so combined that said signal depends upon their relative amplitude.

3. A circuit as in claim 1 in which the demodulated energies are so combined that said signal depends upon their phase relation.

4. A system as in claim 1 including means for applying the signal to regulate the frequency of a microwave generator producing said microwave oscillations.

5. A circuit as in claim 1 in which the pulsating Stark fields are of magnitude effecting sweep by said molecular absorptions through ranges from said higher and lower frequencies to include said desired frequency.

6. A control circuit for use in a system for controlling the frequency of microwave oscillations, said circuit comprising two enclosures each containing gas exhibiting sharp molecular absorption at a frequency displaced from the desired frequency of said oscillations, Stark electrodes respectively disposed in said enclosures, means for applying to each of said Stark electrodes a potential having a direct-current component and a pulsating component, said direct-current components shifting said molecular

absorptions to frequencies respectively higher and lower than said desired frequency and said pulsating components being oppositely phased to swing said shifted molecular absorptions in unison toward and from said desired frequency, means for demodulating the microwave energies respectively transmitted by the gas in each of said enclosures, and a network including non-linear resistances for combining the demodulated energies to produce a unidirectional signal of polarity dependent upon the sense of deviation of the oscillations from said desired frequency.

7. A control circuit for use in a system for controlling the frequency of microwave oscillations, said circuit comprising two enclosures each containing gas exhibiting sharp molecular absorption at a frequency displaced from the desired frequency of said oscillations, Stark electrodes respectively disposed in said enclosures, means for applying to each of said Stark electrodes a potential having a direct-current component and a pulsating component, said direct-current components shifting said molecular absorptions to frequencies respectively higher and lower than said desired frequency and said pulsating components being oppositely phased to swing said shifted molecular absorptions in unison toward and from said desired frequency, means for demodulating the microwave energies respectively transmitted by the gas in each of said enclosures, and a network for combining the demodulated energies to produce a unidirectional signal of polarity dependent upon the sense of deviation of the oscillations from said desired frequency.

8. A circuit as in claim 7 in which the non-linear resistances are oppositely poled and in which their output currents are integrated in a common integrating circuit to produce a unidirectional signal dependent in polarity and magnitude upon the differential amplitude of said output currents.

9. A circuit as in claim 7 in which means is provided to convert one of the demodulated energies to push-pull pulses and in which the network is a phase-comparator for producing a unidirectional signal dependent in polarity and magnitude upon the phase relation of said push-pull pulses to the other demodulated energy.

10. A control circuit for use in a system for stabilizing the frequency of microwave oscillations, said circuit including an error detector, two enclosures each containing gas exhibiting sharp molecular absorption at a frequency displaced from the desired frequency of said oscillations, means for impressing the oscillations upon the gas in said enclosures and for impressing the microwave energies transmitted by the gas to said error detector, Stark electrodes respectively disposed in said enclosures, and means for applying to each of said Stark electrodes a potential having a direct-current component and a pulsating component, said direct-current components shifting said molecular absorptions to frequencies respectively higher and lower than said desired frequency and said pulsating components being oppositely phased to swing said shifted molecular absorptions in unison toward and from said desired frequency.
